5 Claims. (Cl. 123—51)

This invention relates to an engine of the crankless type, under which designation are included all engines having pistons reciprocating in cylinders which are arranged parallel to the power shaft actuated by said pistons.

According to the present invention, two pistons reciprocating in each cylinder actuate severally two crankless shafts which are positioned in axial alignment with each other and geared to a common countershaft, the two shafts being thereby caused to rotate in synchronism. In the form hereinafter described and illustrated in the accompanying drawing, the engine is arranged to operate on the two-stroke cycle. When a plurality of cylinders is used, they are arranged in a circumferential series around the power shaft axis.

Two-stroke crankless engines having multiple cylinders with only a single power shaft are already known, having been described, e. g., in the present applicant's Reissue Patent No. 17,273. By the new construction which is the subject of the present application several important advantages are realized. In particular, the possibilities of torsional vibrations of the long crankless shafts, having comparatively massive slants or swash-plates at each of their ends, according to the prior construction mentioned, are obviated; the total length (and consequent weight) of the shafting is considerably diminished; the difficulty of aligning the bearings (usually 4 or more in number), on the older long shaft is removed, each divided shaft of the new construction requiring two bearings only; the mutual phase-relationship of the two pistons of each pair is rendered easily adjustable by re-assembly in altered angular positions of the gear wheels on their shafts, and the parts of the engine are rendered more readily accessible and more easily assembled. This latter and other constructional advantages are hereinafter more fully explained.

This application is a division of application Serial No. 204,403, filed April 26, 1938.

The drawing is a longitudinal view, partly in section, of an engine constructed according to the invention, the plane of the partial section passing through the axis of a cylinder of the engine, and also through the axes of the two aligned shafts and of the countershaft geared thereto.

The cylinder 14, shown in axial section in the drawing, contains two pistons 13, 13a which respectively actuate the shafts 11, 11a by means of the slipper bearings 15, 15a mounted in the

crossheads 16, 16a of the two pistons, said slipper bearings engaging respectively with each of the two swash-plates or slants 12, 12a which are respectively attached to the shafts 11, 11a and rotate therewith. The axes of the two shafts 11, 11a are in one and the same straight line, the said shafts being rotatably mounted in pairs of journal bearings 20, 20a and 21, 21a and respectively supported longitudinally by thrust-bearings 18, 18a. The cylinder 14 is provided with exhaust ports 45 and scavenge ports 46, these ports being respectively opened and closed by the pistons 13 and 13a in the manner usual in two-stroke engines. The scavenge air may be supplied by a fan 51 gear-driven from the shaft 11a, the delivery ports 52 of the fan casing 53 being connected to the scavenge air chamber 44 by suitable conduits or casings not shown. The exhaust ports 45 deliver into an exhaust chamber 42 and thence through ports 41 to the atmosphere.

A series of cylinders similar to the cylinder 14 and of any desired number and similarly fitted with pistons and members attached thereto, is arranged circumferentially around the common axis of the shafts 11, 11a, one such cylinder 14 being shown in the upper part of the drawing. The two shafts 11, 11a are respectively geared by gear wheels 23, 23a to wheels 24, 24a fixed on the countershaft 10, the said shafts being thereby caused to rotate at equal speeds. The slants 12, 12a consequently rotate in constant and approximately opposite mutual phase relationship, and the pistons 13, 13a reciprocate in approximately opposite phases in the cylinder 14. By suitable change of the angular mounting, of either of the gear wheels 23, 23a upon their respective shafts 11, 11a, or of either of the gear wheels 24, 24a on the shaft 10, the phase relationships mentioned may be varied at will in the construction of several engines otherwise similar, or may be changed from time to time after construction of the engine for the purpose of adapting the engine to a particular speed, or other particular working condition affecting such relationship.

A number of similar engines, each consisting of cylinders 14, pistons 13, 13a, shafts 11, 11a, slants 12, 12a, bearings 15, 15a, 18, 18a, and other parts, as hereinafter described, may be arranged in a circumferential series around the countershaft 10, all being similarly geared thereto so as to form a composite power unit. A power unit of this kind is the subject of a United States patent application Serial No. 204,403, filed by

the present applicant and of which this application is a division. The component engines may either be mounted in a casing 31 common to the whole, as shown in the drawing, or each engine 5 may have an individual casing, the several casings being bolted or otherwise attached together so as to form a frame for the composite unit.

The outer bearing 13 or 13a and thrust bearing 18 or 18a of each shaft 11 or 11a are preferably mounted in a frame member 61 or 61a 10 preferably in the form of a spider detachable from the remainder of the engine casing as shown. By this means either of the shafts 11 or 11a together with the member 61 or 61a and 15 the slant 12 or 12a, the sliders, crosshead and pistons engaging therewith may be inserted in or withdrawn from the engine in the axial direction independently of the assembly of the remainder of the parts of the engine.

20 The mounting of the slants 12, 12a severally upon two relatively short shafts 11, 11a instead of a single long slant shaft, as in engines of prior construction, has the further constructional advantage that space adjacent to the compression 25 spaces at the middle of the lengths of the cylinders 14, which in engines of prior construction is obstructed by the middle portions of the single long slant shaft, are available for the reception of fuel injectors, relief valves, indicator connections and similar fittings which are required to connect with the said compression spaces. Thus, in the drawing the fuel injector 38 of the so-called "long reach" type is inserted into the cylinder 14 adjacent to the countershaft 10 in a line radial 30 to the cylinder and intermediate between the inner ends of the shafts 11, 11a. The existence of such space between the proximate or mutually adjacent ends of the said axially aligned shafts furthermore greatly facilitates the construction 35 of the main casting of the engine, since it removes the necessity for carrying a housing surrounding the shaft through the exhaust and scavenging chambers 42 and 44 and water-cooling chambers 66.

40 The portions of the shafts 11 and 11a extending beyond the bearings 20, 20a are formed with splines 62, 62a. In the end casings 34, 34a are mounted shafts 63, 63a. Sleeves 64, 64a are rotatably supported at their outer ends on shafts 50 62, 62a and at their inner ends slidably engage splines 62, 62a. The gear wheels 23, 23a are mounted by splines on sleeves 64, 64a so as to be slidably thereon and the sleeves are provided with circumferential portions 65, 65a, engageably by 55 suitable shifting means, not shown, by which the sleeves can be readily moved in an axial direction.

Although one specific embodiment of the invention has been particularly shown and described, it will be understood that the invention is capable 60 of modification and that changes in the construction and in the arrangement of the various co-operating parts may be made without departing

from the spirit and scope of the invention, as expressed in the following claims.

What I claim is:

1. An engine comprising a power cylinder, a pair of pistons reciprocating in opposite ends of said cylinder, a pair of rotatable engine shafts aligned on a common axis parallel to the axis of said cylinder and each actuated by one of said pistons, and gearing arranged to transmit motion from one of said shafts to the other so as to maintain them in a constant relative phase of rotation with each other. 5

2. An engine comprising a power cylinder, a pair of pistons reciprocating in said cylinder in approximately opposed phases, said cylinder having a compression space between said pistons, a pair of engine shafts aligned on a common axis parallel to the axis of said cylinder and having their proximate ends spaced apart in the axial direction, operative driving connections between 20 each piston and one of said shafts whereby said shafts are rotated, a fuel injector arranged transversely between said proximate ends of said shafts and entering the said compression space of said cylinder, and a rotatable countershaft mounted 25 parallel to said shafts and geared to each of them so as to synchronize their rotations.

3. An engine comprising a plurality of power cylinders arranged in a circumferential series with mutually parallel axes, a pair of pistons reciprocating in each of said cylinders, a pair of rotatable engine shafts aligned on a common axis parallel to the axis of said cylinders and each rotatably actuated by the pistons reciprocating in adjacent ends of said cylinders, and gearing arranged 30 to transmit motion from one of said shafts to the other so as to maintain them in a constant relation of phase of rotation with each other. 35

4. An engine comprising a power cylinder, a pair of pistons reciprocating in said cylinder, a pair of engine shafts aligned on a common axis parallel to the axis of said cylinder, a member mounted on each of said shafts and engaging with bearing members carried by one of said pistons whereby said member and said shaft are rotated, 40 and means for maintaining synchronism of rotation of said shafts, each said engine shaft being rotatably mounted in a member of the casing of said engine detachable from the remainder of said engine. 50

5. An engine comprising a rotatable power shaft actuated by pistons reciprocating in cylinders arranged parallel to said shaft and in a series extending circumferentially around it, a second power shaft rotatably mounted in axial alignment with the first said power shaft and actuated by pistons each reciprocating in approximately opposite phase to one of the first said pistons and in the opposite end of the cylinder containing such first said piston. 55 60
